METAL DRUM

Edwin V. Sharpnack, Sr., Louisville, Ky., assignor
to Reynolds Metals Company, Richmond, Va., a
corporation of Delaware

Application June 17, 1952, Serial No. 293,894

2 Claims. (Cl. 220—5)

1

This invention relates to a metal drum, and more particularly, to a metal drum having longitudinal tie rods co-acting between ends having deep annular recesses.

It is an object of this invention to provide a metal drum easily and inexpensively manufactured.

It is a further object of this invention to provide a drum having annular ends having deep recesses therein.

It is another object of this invention to provide a metal drum having ends with deep annular recesses, said recesses being united by a plurality of tubular tie rods.

It is a further object of this invention to provide a drum adapted for packing any material, said drum having an easily disengageable head with bayonet lugs to engage lugs of a top annular end.

It is a further object of this invention to provide a cover formed of two discs, the outermost disc having bayonet locking lugs and the inner disc being adapted to engage a sealing ring upon application of pressure of the outer disc during the closing operation.

It is a further object of this invention to provide a drum which is entirely closed, said drum having ends with deep annular recesses, said recesses being connected by tubular tie rods.

These and other objects of this invention will become apparent upon reading the following descriptive disclosure taken in connection with the accompanying drawing, in which,

Figure 1 is an elevation view, partly in longitudinal section, showing a drum having a detachable cover.

Figure 2 is a top view of the drum, partly in section, showing the manner of locking a cover of the drum to the top annular end.

Figure 3 is a sectional view of an annular end and showing a reinforcing bead, and

Figure 4 is a cross-sectional view of a top end showing the manner of locking the cover to the lug of the said top end.

Referring to the drawing, an annular bottom end 1 having a deep V-shaped radial cross-section peripheral recessed channel 2 therein is welded to a plurality of tubular tie rods 3. An annular top end 4 (see Figures 1 and 4) having a deep V-shaped radial cross-section peripheral recessed channel 5 therein is integrally united to tie rods 3 at the line of junction of the inner and outer walls of the channel.

The recessed bottom end 1 may be provided with a concave inwardly disposed central section

2

6 on the inner wall of recessed channel 2, and is further provided with a tubular bead 7 on the outer wall of recessed channel 2. The walls of the annular recessed channel 2 may be tiered to effect greater strength, such a tier being in the inner wall of the recess at point 8. The peripheral recessed channel 2 may be apertured at the points where the tubes 3 are united thereto, so that an unobstructed passageway exists between 10 the V-shaped recessed channels 2 and 5 so that liquid or air may be conducted from one peripheral recessed channel 5 through the tubes 3 and then into the other peripheral recessed channel 2. The outer or exterior wall of the recessed channel 2 may be curved into the shape of a tube of circular cross section so that it forms the bead 7 thereby forming a solid and durable circumferential circular base which supports the weight of the drum and its contents.

20 Referring now to the top end 4, this end is provided with a plurality of inwardly disposed locking projections 9 disposed in the outer wall forming the recessed channel 5 of said top end 4. The inner wall of the recessed end channel 25 4 is provided with a portion 10 of semi-circular cross section at its extremity adapted to receive a solid resilient sealing ring 11 having a semi-circular cross section and made for example from rubber or plastic. The outer wall of the top end 4 may be provided with a circumferential tubular bead 12 which bead substantially fully and cylindrically encloses a circular rod 12x. At the line of junction of the inner and outer walls of the recessed channel 5 the end 4 is provided with a plurality of spaced apart apertures, which apertures are disposed within the spaced apart tubular tie rods 3.

The outer walls of both the bottom end 1 and the top end 4 are inwardly dented a short distance away from the line of junction of their inner and outer walls of the respective recessed channels to accommodate a cylindrical drum body 13. This drum body is welded to the top end 4 at point 14 and to the bottom end 1 at point 15. The tubular tie rods 3 are also welded to the ends 1 and 4 about the orifices in the respective annular members. The bottom of the container may be provided with an additional reinforcing member 16 which may also function as a wear-plate, said wear-plate being circumferentially disposed about the bottom bead 7, which bead is initially enclosed by the curved surrounding extremity of the outer leg of end plate 1.

The cover of the metal drum shown in Figure 55 1 has a top disc 17 having a flat central portion

with a depending obliquely disposed skirt 18 having projections 19 disposed outwardly of said skirt 18. The projections 19 are adapted to engage the undersurface in locking engagement of projections 9, said projections 9 being disposed in the drum end 4. Disposed beneath the outer disc 17 is an inner disc 20, this inner disc 20 having a plurality of circularly disposed elevations 21. The said inner disc 20 is provided with an elevated extremity 22 which extremity has a depending leg 23, said leg 23 being adapted to engage the flat surface of the circumferential resilient sealing ring 11. In closing the drum the cover is placed on to the curved surface 10 of the inner wall of the top drum member 4 with the lugs 19 out of register with the lugs 9. To close the drum into a sealing or a closed position the top cover is rotated so that the lugs 19 engage the lugs 9 in frictional engagement. This rotation of the cover forces disc 17 downwardly against elevations 21 and 22 so that the leg 23 of inner disc 20 engages the sealing ring 11 with a strong grip action due to the spring effect of the distortions of said elevations 21 and 22.

The top disc 17 may be provided with lifting lugs 24 which lugs have an aperture therein for engaging lifting means such as grappling hooks and the like. The body 13 of the drum may be provided with a plurality of spaced apart parallel-disposed pairs of grooved recesses 25. In the embodiment of the invention illustrated in Figure 1 there is provided two V-shaped circular bands or tires 26 and 27, each of these bands having a V-shaped cross section of such a height that the apices of said V-shaped tires 26, 27 are disposed on a line above the beads 7 and 12 of the drum, thereby effecting two points of rolling contact of the drum with a level floor. Clearly the body 13 of the drum on being rolled on a floor is not subject to contact with the floor and any consequent distortion. The bands or tires 26 and 27 are disposed about the body wall 13 in spaced relationship and contact the floor. These bands 26 are provided with flat surfaces 28 which extend outwardly from the V-shaped portion. These flat surfaces 28 are indented into the recesses 25 of the metal drum 13. The bands 26 and 27 may be welded to the body wall 13. Clearly the indentations made in the flat surfaces 28, pressing the metal of said flat surfaces into the recesses 25, function in the sense of keying the bands 26, 27 immovably in place relative to the drum surface 13. The drum of this invention may be made of substantially all commercially available metals but it is preferably made of aluminum. The sheet forming the drum body 13 has a longitudinal weld 29. The end members 1 and 4 are united to the body element 13 by means of a girth weld 30.

While this invention has been described by means of an illustrative embodiment, it is apparent to those skilled in the art that many variations of this embodiment will become readily apparent upon reading the description of this invention taken in combination with the illustrative drawing. However, these non-inventive variations of this invention are intended to be embraced within the scope of this invention appearing in the claims hereinafter.

Having described my invention, what I claim and desire to secure by Letters Patent is as follows:

1. A metal drum adapted to prevent fluid entrapment on the drum head comprising a top annular end member and a bottom annular end member, each end member having an outwardly opening peripheral channel having a V-shaped radial cross section, each of said annular members having a plurality of spaced-apart apertures at the line of junction of the walls of the channel, said bottom member having a concave section integrally united to the bottom edge of the innermost wall thereof, said top member having a plurality of inwardly disposed locking projections on the outer wall thereof, a cylindrical body wall member having its ends secured circumferentially to the outer wall of both of said end members, a plurality of vertically disposed tubes disposed interiorly of said cylindrical body wall member in communication with said apertures of said annular members, and a top circular removable head having an outer disk having a downwardly depending peripheral flange with a plurality of outwardly disposed locking projections and further having an inner disk having a downwardly depending peripheral flange skirt adapted to engage the top edge of the inner wall of the top annular end member.

2. A metal drum adapted to prevent fluid entrapment on the drum head comprising a unitary top annular drum member having an outwardly opening peripheral channel of substantially a V-shaped cross section and further having inwardly disposed locking projections in the exterior wall of said top member, and further having a plurality of spaced-apart apertures at the line of junction of the walls of the channel, a unitary bottom circular end member having an outwardly opening peripheral channel of substantially V-shaped section and further having an inner concave section secured to the inner wall of said channel, a cylindrical body member having its top and bottom ends respectively secured circumferentially to the outer walls of the channels of said top and said bottom end members, a plurality of vertically disposed tubes disposed interiorly of said drum member in communication with said apertures of said top end member and said bottom end member, and a substantially circular removable closure having an outer circular disk with a downwardly depending peripheral flange having a plurality of integral outwardly disposed locking projections and further having an inner disk having a downwardly depending peripheral flange, and a resilient ring disposed in the inner wall of said top annular member and adapted to seizingly engage the depending flange of said inner disk in a hermetically sealed relationship.
